CLAIM

The ornamental design for a reagent cartridge, as shown and described.

DESCRIPTION

FIG. 1 is a perspective view of the first embodiment of a reagent cartridge showing our new design.

FIG. 2 is a top plan view thereof.

FIG. 3 is an enlarged view of the encircled portion in FIG. 1.

FIG. 4 is an enlarged view of the encircled portion of FIG. 1.

FIG. 5 is a perspective view of the second embodiment of a reagent cartridge.

FIG. 6 is a top plan view thereof.

FIG. 7 is an enlarged view of the encircled portion of FIG. 5; and,

FIG. 8 is an enlarged view of the encircled portion of FIG. 5.

The dashed broken lines in the drawings depict portions of the reagent cartridge that form no part of the claimed design. The dot-dashed broken lines in the drawings depict the boundary of the claim and form no part thereof.

The dot-dot-dashed broken lines in the drawings depict the boundary of enlarged views and form no part of the claimed design.

1 Claim, 6 Drawing Sheets(56)
